W. O. ALBIG

BAG PACKAGE

Filed Dec. 17, 1925.

FIG. 1

FIG. 2

Inventor

W. O. Albig

By *Watson E. Coleman*
Attorney

UNITED STATES PATENT OFFICE.

WILLIAM O. ALBIG, OF ADRIAN, MICHIGAN.

BAG PACKAGE.

Application filed December 17, 1925. Serial No. 76,023.

This invention relates to bag packages and has relation more particularly to a package especially designed and adapted for use in connection with a dispensing device of a character disclosed in my Patent No. 1,293,291 dated February 4, 1919, and it is an object of the invention to provide a package of this kind wherein the adjacent bags are interfolded in a manner to allow only a single bag at a time to be withdrawn when the package is applied within this dispensing device.

Another object of the invention is to provide a package of this kind comprising a plurality of interfolded bags together with means disposed around the unfolded edges of the bags for maintaining the package and wherein an end bag has interfolded therewith a member or strip to facilitate the initial extraction of a bag after the package has been applied within the dispensing device.

It is also an object of the invention to provide a package of this kind comprising interfolded bags together with means disposed around the unfolded edges of the bags to maintain the package and wherein an end bag provides a flap to provide a guard or shield for the retaining means at such end of the package.

The invention consists in the details of construction and in the combination and arrangement of the several parts of my improved bag package whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

Figure 1 is a view partly in section and partly in elevation illustrating a package constructed in accordance with an embodiment of my invention and in applied position within a dispensing device;

Figure 2 is a view in perspective illustrating my improved package in its initial assembly.

As herein disclosed, my improved package P comprises a plurality of bags each folded to provide two leaves of equal length with

a leaf of each of said folded bags interposed between the leaves of the adjacent bag and with the folded edges of adjacent bags oppositely arranged, said folded edges being comprised in the upper and lower faces of the package when the package is applied within the dispensing device D. Disposed around the package P and over the unfolded or end edges of the package is a flexible member or strand 1 having its extremities suitably tied, as at 2, at one end of the package and preferably at the central portion of said end. It is to be particularly noted, however, that this retaining member 1 is extended inwardly of the bag flap 3 at the opposite end of the package whereby said flap 3 serves as a guard or shield for said member 1 for a purpose which will hereinafter be particularly referred to. It is to be understood that the flap 3 is arranged at what is to be termed the rear end of the package while the connection 2 of the member 1 is at the front end of the package.

Interfolded with the front bag flap 4 at 80 the front end of the package is a relatively broad strip 5 preferably of heavy paper and of a width materially less than the width of the package.

My improved package P is particularly 85 adapted for use in connection with a dispensing device such as shown in my issued Patent No. 1,293,291 hereinbefore referred to and when applied within the body or box portion 6 of such device, the follower spring 90 7 is placed under compression, said spring having contact with the inner bag flap 3. This spring 7 operates to force the package toward the discharge end of the body or box portion 6 and to continually maintain 95 the folded bags in proper position with respect to the delivery opening 8.

When the package is initially applied within the body or box portion 6, the connection 2 for the member 1 is exposed 100 through the delivery opening 8 so that the same may be readily accessible to release such connection and the member 1 withdrawn from around the package. The withdrawal of this member 1 will not be 105 obstructed by the spring 7 as this member 1 passes across the rear of the package inwardly of the rear end of the bag flap 3 and furthermore, the weight of the package will in no wise hinder such withdrawal of the 110 member 1 as the member is disposed around the sides of the package and is, therefore,

entirely free from the weight of the package. After the member 1 has been withdrawn, a digit, pencil or the like may be inserted through the delivery opening 8 and 5 the outer portion of the strip 5 projected outwardly through such opening so that resultant pull upon said strip 5 will draw the front flap 4 through the delivery opening 8.

While I have hereinbefore specifically referred to package bags it is to be understood that the term bag is to include envelopes and kindred containers.

From the foregoing description it is thought to be obvious that a bag package 15 constructed in accordance with my invention is particularly well adapted for use by reason of the convenience and facility with which it may be assembled and operated, and it will also be obvious that my invention 20 is susceptible of some change and modification without departing from the principles and spirit thereof and for this reason I do not wish to be understood as limiting myself to the precise arrangement and formation of 25 the several parts herein shown in carrying out my invention in practice except as hereinafter claimed.

I claim:—

A container package for use in a dispens- 30 ing body having a delivery opening in its front wall through which the containers are

withdrawn and wherein a follower spring is placed under compression when the package is applied within the body to force the package toward the discharge end of the body, said package comprising a plurality of folded containers, a leaf of one container extending between the leaves of adjacent containers, the folded edges of the containers being comprised in the upper and lower 40 faces of the package when the package is applied within the dispensing body, a flexible member disposed around the package and over the unfolded edges of the package, the extremities of the flexible member being 45 tied at the front end of the package when applied within the body, the outer leaf at the rear end of the package overlying the portion of the flexible member extending across the rear end of the package to provide a shield on the rear portion of the flexible member when the package is first applied within the body and with which the follower spring directly contacts, the tied extremities of the flexible member being 50 readily accessible when the package is initially applied through the delivery opening in the front wall of the body.

In testimony whereof I hereunto affix my signature.

WILLIAM O. ALBIG.
